UNITED STATES PATENT OFFICE.

VICTOR KOBLER-STAUDER, OF ZURICH, SWITZERLAND.

TYPE-WRITING MACHINE.

1,245,926.

Specification of Letters Patent.

Patented Nov. 6, 1917.

Application filed May 23, 1916. Serial No. 99,323.

To all whom it may concern:

Be it known that I, VICTOR KOBLER-STAUDER, a citizen of the Republic of Switzerland, residing at Zurich, Huttenstr, 62,

5 Switzerland, have invented certain new and useful Improvements in Type-Writing Machines; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to means for preventing the operator of a typewriting machine from writing too close to the bottom edge of the work sheet, by automatically locking the platen of the typewriter before 20 the bottom edge of the work sheet has passed the printing point.

The accompanying drawings illustrate several embodiments of the invention.

A first embodiment is shown in Figs. 1 to 25 7, in which—

Figure 1 is a side elevation,

Fig. 2 is a plan,

Fig. 3 is a section on line A—B of Fig. 2,

Fig. 4 is a section on line C—D of Fig. 2.

30 Fig. 5 is a section on line E—F of Fig. 1,

Figs. 6 and 7 show the mechanism in two different positions,

35 Figs. 8 and 9 are schematic views of different positions of a section embodiment of the invention,

Figs. 10 and 11 show a third embodiment,

Figs. 12 and 13 a fourth and

Fig. 14 a fifth embodiment of the invention.

40 A last embodiment is illustrated by the Figs. 15 to 20, of which—

Fig. 15 is a side elevation and

Fig. 16 a top elevation.

45 Fig. 17 shows the mechanism when locked, and

Figs. 18 to 20 show details hereinafter referred to.

The same letters of reference are employed to denote like parts in all the views.

50 Referring to Figs. 1 to 7, 1 is the frame of a typewriter, 2 is a platen-frame, 3 is a platen around which the sheet is wound. 4 is a ratchet-wheel fast with the platen 3 and cooperating with a dog 5 to feed the sheet in 55 the usual way. A plate 6 is arranged to swing about the platen axle and has a cam

surface at 9 adapted to cause a detent-roller 8 to release the platen 3, this effect being obtained by depressing a lever 7 arranged on said plate 6. A lever 10 is also rotatable 60 about the platen axle and carries a link piece 11 with guiding face 12, on which rests a projection 13 of the dog 5, so that by adjustment of lever 10 the moment when dog 5 engages the ratchet 4 can be controlled and the 65 line-spacing effected. 14 is a guide bar for the carriage-truck, and 15 is a bar parallel to the platen 3 and has attached to it a sheet metal guard 16 which extends downward 70 closely to the platen 3.

The parts so far described are known and generally used for typewriting machines if not in exactly the same form.

Now the plate 6 has two pins 16' and 17, the latter being guided in the slot 18 of a 75 lock plate 19. Lock plate 19 carries a rack 20 adapted to engage or disengage a gear 21 which is fast on the platen axle. Two stop faces 22 and 23 are provided on lock plate 19 and serve to limit the movement of the latter in both directions by striking the bar 14 and the hub of gear 21 respectively. A link 24 connects the lock plate 19 to a rocking shaft 15 which is rotatable within a sleeve 25 held in a bend of the cover 16. This link 80 24 is loose on shaft 15 and is controlled by a spring 26 which is wound up on the shaft 15 and presses with one end against a pin 27 fixed upon the link 24 and with the other against a second pin that is arranged upon a crank 27' fast on the shaft 15. On this shaft 15 are further fast a lever 28 that may be engaged by the pins 16' and 27, and two brackets 29 whose free ends are connected by means of a rod 30. 31 is a sheet-metal paper 90 guide curved at its upper end to hold the guard 16 where the latter is bent around the sleeve 25, and bent to form a groove 32 resting against guard 16 and into which the rod 30 may enter.

100 The sheet *a* (Fig. 4) to be written upon is passed in between the paper guide 31 and the feeler rod 30, so that the sheet covers groove 32 and by its inherent stiffness prevents the feeler 30 from entering said 105 groove. Therefore, as long as the sheet covers this groove 32, the spring 26 keeps the pin 27 of link 24 pressed against the lever 28, whereby the link 24 is held in a somewhat raised position and the lock plate 19 110 pressed against the hub of gear 21. In this position the rack 20 is out of mesh with the

gear 21, so that the platen 3 may rotate and the paper continue to be fed without actuating the lock plate 19. As soon, however, as the bottom edge of the sheet *a* passes under the feeler 30 and uncovers the groove 32, the feeler 30 trips, enters said groove and thereby turns shaft 15 in the direction of the pointer 33 in Fig. 1. Accordingly, lever 28 is lowered to rest against pin 16, and, at the same time, link 24 is rotated in the direction of pointer 33 under the influence of pin 27, and the lock plate 19 travels as indicated by pointer 34 in Fig. 1, so that rack 20 engages the gear 21. Then as the platen 3 continues to rotate, the lock plate 19 proceeds on its way in the direction of the pointer, and as shaft 15 is locked through lever 28 being arrested by the pin 16', the spring 26 is strained. Next, the lock plate 19 strikes with its face 22 against bar 14 (Fig. 6) and the platen is locked, thus indicating to the operator that a fresh sheet should now be commenced. The length of rack 20 and the size of gear 21 on the one hand and the distance between groove 32 and platen 3 on the other hand are so chosen that after rack 20 has engaged gear 21, the sheet will continue to travel for a distance permitting to obtain, at the moment when the platen 3 is locked, the desired width of margin between the last line and the bottom edge of the sheet. Now lever 7 is pulled as shown by pointer 35 in Fig. 6, so that pin 17 raises the lock plate 19 and thereby disengages rack 20 from gear 21. Simultaneously, pin 16' lifts lever 28, so that shaft 15 is rocked and the lock plate 19 returns to the position shown in Fig. 7 under pressure of spring 26. The sheet *a* can now be removed from the typewriter and a new sheet inserted, and after the lever 7 has been pushed back to its normal position, the lock plate occupies again its initial position as in Fig. 1 and the feeler 30 lies upon the new sheet.

Referring now to Figs. 8 and 9, the mechanism there illustrated comprises a gear 36 to take the place of the rack 20 in the first embodiment of the invention. This gear 36 can be made to engage or disengage the gear 21 and is mounted on a pin 39 which is fixed on a lock plate 37. The lock plate 37 has a slot 38 to engage the hub of gear 21. The gear 36 is under the action of a spring 40 which is wound upon the pin 39 and rests at one end against a pin 43 of an arm 42 which is fast on the pin 39, while its other end engages a pin 41 fast on the gear 36. Pointer 44 shows the direction in which the spring 40 tends to turn gear 36. A stop 45 is adjustably mounted in a slot 46 of said gear 36. To the lock plate 37 is journaled a bell crank lever 47 acted upon by a spring 48, whose ends bear against a pin 49 of the lock plate 37 and against the lever 47 respectively. Under action of this spring 48, one arm 47' of the bell crank lever 47 is pressed against pin 49 and may be engaged by a pin 50 mounted on the face of gear 36.

In the path of the other arm of lever 47 is bar 14, so that the movement of this lever 47 is limited by pin 49 on the one and by bar 14 on the other side.

A two-armed lever 52 is pivoted at 53 to the platen-frame 2, is connected to the plate 6 by means of a link 51 and also pivotally connected to the lock plate 37.

Normally, the gear 36 is in mesh with the gear 21 and before a sheet is introduced into the machine, the arm 47' of bell crank lever 47 presses against pin 49, while pin 50 bears against this arm 47' and the lever 47 is clear of the bar 14. If now a sheet is inserted into the machine and written upon, the line-spacing movement of the platen will cause the gear 36 to rotate in the direction shown by pointer 44 and thereby to strain spring 40, until the stop 45 strikes the arm 47' on the side where it rests against pin 49, so that lever 47 is turned against the action of its spring 48. Then lever 47 is arrested by the bar 14 and prevents further rotation of the gear 36 and therefore also of the platen. In order to release the platen for removing the sheet from the machine, the plate 6 is turned by means of the lever 7 as indicated by pointer 35. This causes a rocking movement of the lever 52 and lock plate 37 is made to travel in the direction indicated by pointer 54; this results in disengaging the gear 36 from gear 21, whereupon the former, under action of its spring 40 rotates, as indicated by pointer 44, and returns to its starting position (Fig. 9). Now, by turning the platen, the sheet may be removed from the machine and lever 7 pushed back into its initial position.

By adjusting the stop 45 in the slot 46, the moment when the locking of the platen takes place may be delayed or advanced so that the margin remaining at the bottom of the page after the platen has been locked, may be obtained of any desired width, that is to say, the device may be adjusted for sheets of different length to obtain any desired width of margin.

Referring now more particularly to Figs. 10 and 11, the third example of carrying the invention into effect comprises, as in the first example shown in Figs. 1 to 7, a paper feeler 30 adapted to enter a groove 32 in a paper guide 31 and connected to a rocking shaft 15 by means of brackets 29. Loose upon this shaft 15 is a lever 55 connected to the plate 6 by means of a link 56. Rigidly connected to this lever 55 is a second lever 57 linked to a lock plate 59 which carries a toothed wheel segment 58. Fast upon shaft 15 is a bell crank lever having arms 60 and 61. A tension spring 130

62 is attached with one end to arm 60 and with the other to the lock plate 59, which is thereby normally held against a pin 63. This pin 63 is adapted to engage a projection 64 of the plate 6 but is normally clear of it.

As long as the sheet *a* covers the groove 32, feeler bar 30 holds the pin 63 in a raised position, so as to keep segment 58 clear of the gear 21. As, however, the bottom edge of the sheet leaves the groove 32 behind and allows the feeler 30 to trip, bell crank lever 60, 61 will be slightly depressed and its pin 63 will sink until arrested by the projection 64. This movement of the lock plate 59 causes the segment 58 to engage gear 21 and as the platen 3 continues to rotate, said lock plate is moved toward bar 14, until it is arrested by its projection 65 engaging a notch 66 of the bar 14, whereby the platen 3 is locked, as shown by the full lines in Fig. 11. In order to remove the sheet and return the mechanism to its starting position, the plate 6 is rotated as shown by pointer 35 and the link 56 causes lever 57 to swing outward, so that segment 58 is disengaged from the gear 21. While the lock plate 59 has been moved downward, the spring 62 has been strained and now forces the lock plate to swing upward until it strikes the pin 63, as shown by the dot-and-dash lines in Fig. 11. Now a new sheet may be inserted into the machine and then plate 6 returned to its initial position, so that feeler bar 30 now rests on the surface of the new work sheet and the lock plate 59 returns to its initial position as shown in Fig. 10.

Referring now to Figs. 12 and 13, the example of execution there shown comprises a toothed wheel segment 67 forming part of a lock plate 68 and normally engaging the gear 21. Lock plate 68 is journaled to one arm 69 of a three-armed lever that is loosely mounted on a bar 72, the latter being rigidly connected with the platen-frame. The second arm 70 of the three-armed lever carries a nut 73, in which a set screw 75 may be adjusted to limit the upward movement of the lock plate 68. At its free end, this arm 70 is formed into a pointer arranged to work along a graduation 74 on the segment 67. The third arm 71 of said three-armed lever is connected to the plate 6 by a link 76 and to the lock plate 68 by a tension spring 77.

As in operating the machine the platen 3 rotates, the lock plate 68 is caused to move toward the bar 14, while the pivot of this movement is fixed in its position through the said three-armed lever being locked by means of the link 76 and the plate 6. This movement of lock plate 68 strains the spring 77 and continues until a projection 78 of the said lock plate enters a notch 66

in the bar 14, whereby the platen is locked. In the same way as before described, the platen is released by turning lever 7 in the direction shown by pointer 35, the lock plate 68 being arrested by striking the set screw 75. By adjusting the screw 75 in its nut 73, the movement of the lock plate 68 may be controlled and indicated by means of the pointer on the graduation 74.

Fig. 14 shows that instead of the lock plate 68 being arrested by engaging the rod 14 of the machine, a stop 79 may be adjusted upon the segment 67 by means of a screw 80 so as to cover a variable number of teeth. This stop projects beyond the teeth of the said segment 67 and causes the locking of the platen 3 by striking against the gear 21.

Where the mechanism comprises a feeler bar as described, it is also possible to obtain an adjustment of the moment of locking the platen, to which purpose the stop face 22 or the projection 65 may be adjustably arranged.

Referring now more particularly to Figs. 90 to 20, the sixth embodiment of the present invention therein shown has the advantage, over the mechanisms described, to be simpler in its design and easier to operate and to adjust. In the same manner as already described, the machine is provided with a paper feeler 30 and groove 32. Fast on the axle 4^a of the platen 3 and outside of the platen-frame 2 is arranged a sleeve 81, upon which are rotatably mounted two disks 82, 83 connected to each other by bolts 84 and 85. Under action of a spring 87 the disks 82, 83 tend to follow the rotating movement of the platen 3, said disks constituting members of a friction clutch to connect the platen with a rotary member, hereinafter described. The disk 82 has a projection 101, a cam face 86 and a stop 102. The usual detent-roller 8 engaging the line-spacing gear, cooperates with cam face 86 and stop 102. Lying against disk 83 is a plate 88 having an arm 89 which carries a button 90. The disk 83 has notches 91 in its circumference, which are engaged by a pawl 92 linked to the plate 88 and adapted to effect the coupling of the said plate with the pair of disks 82, 83.

Fast upon the shaft 15 is a lever 93 whose free end projects into the space between the disks 82 and 83, and branches out into two arms 94 and 95, the latter ending in a hook 96.

Now, as long as the work sheet covers groove 32 and holds the feeler 30 in a raised position, the hook 96 is in engagement with bolt 84 thereby preventing the disks 82 and 83 as well as the plate 88 from following the platen 3 in its rotation which takes place as indicated at 97 (Fig. 15). As soon, however, as the bottom edge of the sheet clears

the groove 32, and the feeler bar 30 drops into it, lowering lever 93 so that hook 96 releases the bolt 84. As the platen continues its feeding motion, the spring 87 causes the disks 82, 83 and plate 88 which is now locked by the friction to plate 83 to rotate until arm 89 after accomplishing more than half a revolution, comes into the path of the bar 14, and as the carriage truck proceeds, the 5 arm 89 strikes the end face of the said bar 14, so that the carriage truck is locked and the operator thus notified that the margin left at the bottom of the sheet has the desired width. In order to remove the sheet, the 10 button 90 is brought back turning the plate 88 and the disks 82, 83 in a clockwise direction until the roller 8 after having been engaged by cam face 86 strikes the stop 102 and thus locks the disks 82, 83 and the plate 15 88. Simultaneously with the described rotation of the said disks, the bolt 84 comes into contact with the lower side of arm 94 and thus causes lever 93 to rise and feeler bar 30 to be lifted out of groove 32, whereupon 20 a new sheet can be introduced. When the button 90 is released, the position of the disks 82, 83 and of the plate 88 is maintained unchanged with relation to the platen 3 and only when, at the next sliding movement of the carriage truck, the projection 25 101 engages a beveled face 99 of a stop 100, the disks 82, 83 and the plate 88 are caused to rotate until the hook 96 engages bolt 84, whereby the disks are locked and the whole 30 mechanism is returned to its initial position. 35

By placing the pawl 92 into one or the other of the notches 91, the position of plate 88 in relation to the disks 82, 83 may be 40 altered, whereby the moment of locking the carriage truck 2 is advanced or delayed at will, so that the width of the margin at the bottom of the sheet can be varied.

In order to enable the operator if necessary to continue to write a few words after the carriage truck has been arrested, one or more notches 98 may be provided in the 45 guide bar 14. Thus, when the arm 89 has struck the face 14' of said bar, the operator 50 may, by hand, lift this arm 89 to clear said face and the writing may continue, but only until the engagement of arm 89 in the next notch 98 again locks the machine.

This last embodiment of the present invention is of a particularly simple design 55 and easily manipulated and its attachment to a type writing machine does not render the latter either much more expensive or more cumbersome than any machine without an attachment.

I claim:

1. In a type-writing machine, the combination with a platen, a detent and a detent 60 release mechanism; of mechanism for determining the bottom margin of the sheet, re-

set to operative position by said detent release mechanism.

2. In a type-writing machine, the combination with a platen, a detent and a detent 70 release mechanism; of mechanism for locking the platen to determine a margin at the bottom of the sheet and re-set to operative position by the detent release mechanism when it is re-set to its non-release position.

3. In a type-writing machine the combination with a platen, a detent and a detent 75 release mechanism; of mechanism for determining the bottom margin of a sheet, and means included in both mechanisms whereby the margin determining mechanism is automatically re-set to operative position by the movement of the detent release mechanism to its non-release position.

4. In a type-writing machine, the combination with a platen, a detent and a detent 80 release mechanism including a rotatable member; of mechanism for determining the bottom margin of a sheet co-operating with said platen, means to connect said member and the margin determining mechanism, said 85 member operating to re-set the latter mechanism and return the detent release mechanism for normal operation of the platen.

5. In a type-writing machine, the combination with a platen, a detent and a detent 90 release mechanism; of mechanism for determining the bottom of a sheet, re-set by the detent release mechanism, and means to adjustably connect the two mechanisms together to vary the bottom margin.

6. In a type-writing machine, the combination with a rotatable platen, a detent and a detent release mechanism including a rotatable actuating member; of sheet-controlled bottom margin determining mechanism co-operating with said platen, and a pawl to adjustably connect said member and the margin determining mechanism, said member operating to re-set the margin determining mechanism and simultaneously to 105 return the detent release mechanism for normal operation of the platen.

7. In a type-writing machine, the combination with a rotatable platen, a detent and a detent release mechanism including a rotatable member; of a bottom margin determining mechanism comprising a clutch arranged to connect said member and platen, and controlled lever mechanism to normally hold the clutch stationary and permit said 110 member to remain stationary while typing the body of the sheet.

8. In a type-writing machine, the combination with a rotatable platen, a detent and a detent release mechanism including a rotatable member; of a bottom margin determining mechanism comprising a clutch arranged to connect said member and platen, controlled lever mechanism to normally hold the clutch stationary and permit said mem- 115 120 125 130

ber to remain stationary while typing the body of the sheet, and means to adjustably position said member about the platen axis to vary the bottom margin.

- 5 9. In a type-writing machine, the combination with a rotatable platen, a detent and a detent release mechanism including a rotatable member; of sheet controlled bottom margin determining mechanism including 10 a forked lever one of whose fork arms is provided with a hook, a clutch on the platen shaft including a bolt engaged by said hook to hold the clutch inoperative until the margin determining mechanism is actuated, 15 and thereafter said clutch connects said member and platen.

10. In a type-writing machine, the combination with a rotatable platen, a detent and a detent release mechanism including a rotatable member on the platen shaft; of a sheet controlled bottom margin determining mechanism including a forked lever one of whose fork arms is provided with a hook, a friction clutch on the platen shaft including 25 two angularly displaced bolts one of which is engaged by said hook to hold the clutch inoperative until the margin determining mechanism is actuated, and the other of which acts as a positive stop to the rotation of the clutch.

11. In a type-writing machine, the combination with a platen, of a feeler bar, a groove to receive it, brackets, a shaft, a lever fast on said shaft, a clutch yieldingly connected 30 to said platen, two arms on said lever, a hook on one of said arms, two bolts in said

clutch, a plate adjustably connected to said clutch, an arm on this plate, a guide bar stop fast in the machine frame to engage said arm and means for unlocking said 40 platen.

12. In a type-writing machine, the combination with a platen, of a sheet controlled lever, two arms on this lever, a hook on one arm, a clutch, two bolts in said clutch to engage said arms, a plate adjustably connected to said clutch, an arm on said plate, means for engaging said arm, a cam face and stop on said plate and of means for returning said plate into its initial position. 50

13. In a type-writing machine, the combination with a platen, of a sheet controlled lever, an arm on this lever, a hook on said arm, a clutch spring connected to said platen, a bolt in said clutch, means for arresting said 55 platen attached to said clutch, means for unlocking said platen provided on said plate, a projection on said plate, and of a beveled stop to engage said projection.

14. In a type-writing machine, the combination with a platen, a guide bar for the platen carriage, a detent and a detent release mechanism; of mechanism for determining the bottom margin of the sheet limited in its operation by the guide bar. 60

In testimony that I claim the foregoing as my invention, I have signed my name in presence of two subscribing witnesses.

VICTOR KOBLER-STAUDER.
